PAPER SHEET FILING DRAWER

Eduardo Alonso Planas, Mariana, Cuba

Application February 4, 1948, Serial No. 6,160

2 Claims. (Cl. 129—16)

1

This invention relates to filing drawers for odd paper sheets, and is more particularly concerned with the filing drawers which are commonly used in accounting offices and in which the odd paper sheets are arranged in alphabetical order.

The object of this invention is to provide a filing drawer of that kind wherein the pile of upstanding odd sheets rests with one end against a slightly inclined transverse partition which is slidably arranged on the drawer bottom and is adapted to be adjusted in position according to the thickness of the pile of filed odd sheets. Adjacent the pile is slidably disposed, laterally to the space occupied by the upstanding odd sheets, a spacer adapted to be inserted into the pile of sheets to occupy the space of a temporarily removed sheet and thus serve as an indicator which will enable the user to locate the place assigned to the previously removed sheet without necessity of looking for the proper place corresponding to such removed sheet according to the alphabetical grouping order of the filed sheets. Thus, considerable time is saved in the handling of filing drawers of this kind. The filing drawer is simple and inexpensive in construction and has considerable advantages in the daily handling of filed odd sheets in banking offices and the like.

The invention is described with reference to the figures of the accompanying drawings, of which:

Fig. 1 is a top plan view of the filing drawer for odd paper sheets.

Fig. 2 is a side elevational view of same.

Fig. 3 is an end elevational view of same.

Fig. 4 is a longitudinal vertical section view on line 4—4 of Fig. 1.

Fig. 5 is a side elevational view partly broken away to show the slidable transverse partition and its adjustment mechanism in its outer limiting position.

Fig. 6 is a detailed view in horizontal section showing at the end wall of the drawer a paper sheet covered with a movably mounted glass plate to keep the note-bearing sheet visible to the user.

The drawer of this invention is composed of a supporting base 1, preferably made of wood, to which are secured two longitudinal lower wooden bolsters 2 adapted to maintain the base 1 spaced from the surface on which the drawer is placed for its use. The base 1 forms the bottom of a drawer which latter is completed by two vertical side walls 3 and 4, a slightly inclined end wall 5 between said side walls and arranged at a point about one-third the length of the drawer and projecting upwardly above the side walls 3 and 4, 55

2

and a slightly inclined end wall 6 which is slightly lower than the side walls 3 and 4.

The longitudinal space between the walls 5 and 6 is provided to receive a pile of upstanding odd paper sheets 7 such as commonly used in banking offices and the like for recording clients' datas and which are usually grouped in alphabetical order of the clients' names. The pile of odd sheets 7 rests with the lower edges of the sheets on a sheet having a rough or grained surface such as sandpaper 8 laid on the supporting base 1, and the pile of odd sheets 7 adjustably rests with the last sheet situated farthest away from the inclined wall 5 of the drawer, against a raised partition 9 which is slightly inclined oppositely to the inclination of the wall 5, so that the space adapted to receive the pile of odd sheets 7 will become wider from bottom to the top. The raised partition 9 is slidably supported by means of an angular metal plate 10 secured to the center of the lower portion of the rear face of the partition 9 and projects downwardly in vertical direction. The lower edge of the plate 10 has an opening 11 formed therein through which extends a guide bar 12 horizontally mounted in a recess 13 formed in the central longitudinal portion of the base 1. The guide bar 12 is secured with one end in a horizontal hole 14 formed in the outer end of the recess 13 and with its other end in a horizontal hole 15 formed in the inner end of the recess 13. The bar 12 has formed therein a series of spaced apart holes 16 through any one of which an angular stop 17 can be selectively inserted for securing the partition 9 in the selected position. The partition remains spaced apart from the top face of the base and the rough surface 8 so as not to scrape the latter.

The partition 9 is slidably adjusted lengthwise the guide bar 12 by means of a metal yoke 18 having its ends pivotally connected by means of horizontal pins 19 with angular brackets 20 each secured by a screw 21 to a lateral portion of the rear face of the partition 9 and projecting backward perpendicularly to the partition 9. Above the brackets 20 there are secured to the lateral portions of the rear face of the partition 9 slide guides each formed by two plates 22 and 23 spaced apart by collars 24 and 25 mounted on screws 26 and 27 passing through holes which are formed in said plates 22 and 23 and being secured to the partition 9. The inner spaces of said slide guides between each pair of plates 22 and 23 are adapted to receive the inward bent ends of two metal rods 28 and 29 which at their other outward bent end are rotatably supported

in metal sockets 30 and 31 secured to the inner face of the vertical side walls 3 and 4 of the drawer, the metal rods 28 and 29 being joined together between their ends by a horizontal pivot bar 32 passing through holes formed in the lateral portions of the yoke 18 and in the rods 28 and 29, thus forming a pivotal connection between the yoke 18 and the oscillatory bars 28 and 29 arranged in crossed position diagonally with the lateral portions of the yoke 18, as it is shown in Figs. 2 and 4 of the drawings. The yoke 18 is made of a flat rod and it has its free end bent angularly to form a handle for operating the described mechanism for causing the partition 9 to slide lengthwise of the supporting base 1 forming the drawer bottom.

At the outside of one of the drawer side walls there is disposed a sheet spacer consisting of a finger 33 which consists of a metal strip bent perpendicularly at its outer end to form a support for the user's fingers so that it is adapted to be pressed downwardly or upwardly when the finger 33 is to be inserted between two odd sheets of the pile 7 or withdrawn therefrom. The strip 33 is mounted pivotally by means of a horizontal pin 34 at the forked top end of a slidably adjustable vertical post 35 which is also made of a metal strip bent perpendicularly upon itself at an intermediate point thereof and has at its lower end an opening through which extends a guide bar 36 extending horizontally in parallel arrangement to the outer face of the vertical side wall 3 and spaced therefrom by collars 37 and 37' mounted on screws 38 and 39 which secure said guide bar and collars to said vertical side wall 3. In order to prevent the finger 33 from slipping in its raised position beyond the end wall 5 limiting the drawer, there is provided a stop 40 fixed to one of the side walls 41 which will be later described.

The inclined end wall 5 forms the rear wall of a closed compartment that is formed at the end of the drawer that is opposite the mechanism for moving the partition 9 by two tapered side walls 41 forming an upward extension of the side walls 3 and 4 of the drawer, a front wall having a raised portion 42 inclined oppositely the wall 5 and a horizontal portion 43 to the fore edge of which is hinged by hinges 44 an angular lid 45 which normally rests with its lower edge on the top face of the base 1, and a top wall 46 secured to the top edges of the wall 5 and wall portion 42 and which projects at the front of the latter. A transparent plate 49 for instance made of glass, is arranged between two lateral jambs 47 and a stop bar 48 fixed in horizontal transversal position on the horizontal portion 43 and is adapted to cover any note-bearing paper sheet 50 which it is desired to display permanently visible to the user. Said transparent plate 49 is kept slightly spaced from the wall portion 42 by the fork 51 formed at the end of a sheet-metal arm 52 passing through a slot 53 which is formed at one side of the wall portion 42 adjacent one of the side walls 41 and which is pivotally mounted on a horizontal screw 54 secured to the inner face of said wall, said arm 52 having beyond the fork 51 an outwardly extending lateral lug 55 serving as a hold for the fingers when it be desired to cause the transparent sheet 49 to tilt about its lower edge for facilitating the insertion or withdrawal of a paper sheet 50. The inner space of the compartment is adapted to store writing articles, such as inkstands, pen-

cils or the like. The angular lid 45 has secured thereto a small angular plate 56 projecting at one side and ending in a lug 57 for raising said lid 45 from its seat.

The mode of operation of this filing drawer is as follows: When it is necessary to increase the number of odd sheets 7, the stop 17 is removed, and by gripping the raised central portion of the yoke 18, the partition 9 is caused to slide backward on the lower guide bar 12 to a suitable position in which it is fixed by inserting the stop 17 in the hole 16 that is nearest to the slideable plate 10. When one of the sheets has been withdrawn from the sheet pile 7, the finger 33 is operated by causing it to rotate downward in front of the place occupied by the withdrawn sheet until it projects in the pile 7 right in the place formerly occupied by the withdrawn sheet. When it is desired to reinsert the withdrawn sheet, such insertion can be made without any loss of time, for the finger 33 will indicate the withdrawn sheet's place. To withdraw the finger 33, the handle thereof is pressed downwardly, whereupon the finger 33 will be raised outwardly from the pile 7 by rotating on its pivot 34.

It is obvious that changes may be made in the slideable assemblage and operative mechanism for the adjustable partition of the drawer, as well as in the shape and assemblage of the sheets spacer, without thereby altering the essential character of the invention, which is such as claimed hereinafter.

What I claim is:

35. 1. A filing drawer for odd sheets, comprising a flat bottom base provided with a recess lengthwise its central longitudinal line, a guide bar extending longitudinally within said recess and provided with inter-spaced vertical holes, vertical side walls attached to said base, a stationary inclined wall at one end, a second stationary wall at the other end, a raised transversal partition inclined oppositely the inclined end wall, a plate slidably mounted on the guide bar and secured to the rear face of the partition to maintain the latter raised above the bottom base, brackets secured to the lower portion of the rear face of the partition at each side, a handling yoke having its ends pivotally connected to the ends of said brackets, slide guides fixed to the top portion of the rear face of the partition at its slides, lateral rods outside the yoke and rotatably mounted with one end in said side walls and having their other end slidably connected to said slide guides, pivotal connections between the lateral portions of the handling yoke and said lateral rods at intermediate points of their lengths respectively, and an angular stop adapted to be inserted in one of the guide-bar holes to fix the transversal partition in adjusted position.
36. 2. A filing drawer for odd sheets, comprising a flat bottom base provided with a recess in its central longitudinal line, a guide bar extended longitudinally within said recess and provided with inter-spaced vertical holes, vertical side walls attached to said base, a stationary inclined wall at one end, a second stationary wall at the other end, a raised transversal partition inclined oppositely to said inclined end wall, an angular metal plate secured with its upper inclined portion to the rear face of the transversal partition and having in its vertically positioned lower portion an opening through which said guide bar extends, so as to maintain the partition spaced

above the bottom base, brackets secured to the lower portion of the rear face of the partition at each side thereof, slide guides fixed to the top portion of the rear face of the partition at each side thereof, lateral rods rotatably mounted with their lower ends in said side walls and having their upper ends slidably connected with the slide guides, a handling yoke having lateral portions crossed diagonally with said lateral rods adjacent thereof and having their lower ends pivotally connected with the ends of said brackets, a horizontal bar pivotally connecting the crossing points of the lateral rods and the lateral portions of the handling yoke, and an angular stop adapted to be selectively inserted in one of the holes of the guide bar behind the transversal partition to fix said partition in ad-

justed position according to a predetermined thickness of the pile of odd sheets to be inserted in said drawer.
